UNITED STATES PATENT OFFICE.

ALBERT ABRAMS, OF SAN FRANCISCO, CALIFORNIA.

TOOTH-BRUSH.

No. 864,054.

Specification of Letters Patent.

Patented Aug. 20, 1907.

Application filed October 7, 1905. Serial No. 281,797.

To all whom it may concern:

Be it known that I, ALBERT ABRAMS, a citizen of the United States, residing at San Francisco, in the county of San Francisco and State of California, have 5 invented new and useful Improvements in Tooth-Brushes, of which the following is a specification.

This invention relates to tooth brushes, and has for its objects to provide a comparatively simple, inexpensive device of this character which may be readily 10 manipulated, and one which in practice will serve at a single operation to brush the front and rear faces and crowns of the teeth.

A further object of the invention is to provide a brush having a handle equipped with an instrument 15 for scraping the teeth and cleansing the tongue.

With these and other objects in view, the invention comprises the novel features of construction and combination of parts more fully hereinafter described.

In the accompanying drawings: Figure 1 is a perspective view of a brush showing one form of embodiment of the invention. Fig. 2 is a similar view showing a slightly different embodiment of the invention. Fig. 3 is a cross section taken on the line 3—3 of Fig. 1.

Referring to the drawings, it will be seen that the 25 brush, which is composed of any suitable material, comprises as a whole a handle 1 and a head 2, the latter, which is of substantially U-shape in cross-section, being equipped on its inner face with a continuous rubbing or cleansing surface preferably composed of 30 bristles 3 applied to and arranged to project perpendicularly from the side portions 4 and crown 5 of the head 2, the side portions of which are curved in parallel relation and throughout the entire length of the head on a forwardly pitched arc conforming to the teeth, 35 whereby when the brush is in action, one of the side walls will follow the inner curvature and the other side wall the outer curvature of the row of teeth.

As seen in Fig. 1, the head 2 is extended longitudinally relative of the handle 1, while in the form of 40 brush illustrated in Fig. 2 the head is arranged at right angles perpendicularly to the longitudinal axis

of the handle, it being noted that in other respects the constructions are identical. The handle 1 is terminated at its rear end in a flattened angularly bent portion 6 constituting a scraper for removing tartar 45 and similar accumulations from the teeth and for scraping the tongue. To facilitate its use it will be observed that the handle 1 is in the same plane as the crown portion of the head, so that, when the brush is placed over the teeth, it is only necessary to have 50 the mouth open just far enough to allow the crown portion to pass between the teeth, thereby lessening the strain upon the jaws and preventing contact of the handle with the lips or gums.

In practice, the head 2 is seated over the teeth of 55 the operator, the brush being thereafter manipulated in the ordinary manner for cleaning the teeth, the front and rear faces and crowns of which latter will be simultaneously acted upon and cleaned in a single 60 operation.

From the foregoing it is apparent that I produce a simple device admirably adapted for the attainment of the ends in view, it being understood that in attaining these ends minor changes in the details herein set forth may be resorted to without departing from 65 the spirit of the invention.

Having thus fully described my invention, what I claim as new is:

A tooth brush comprising a handle with a head there-with, said head being constructed substantially U-shaped 70 and longitudinally curved, the handle being arranged above one side of the head and integral with the central portion of the crown of the head so that the head will extend on opposite sides of the handle, rubbing surfaces secured continuously around the inner face of the head, and 75 one portion or row of said rubbing surface depending vertically from the central portion of the head so as to contact with the edges or crown portions of the teeth, substantially as specified.

In testimony whereof, I affix my signature in presence 80 of two witnesses.

ALBERT ABRAMS.
